UNITED STATES PATENT OFFICE.

CHRISTIAN KECK, OF CRESCENT SPRINGS, KENTUCKY, ASSIGNOR TO C. KECK MANUFACTURING CO., OF CINCINNATI, OHIO, A FIRM CONSISTING OF CHRISTIAN KECK AND HARRY H. HYAMS.

MECHANICAL MOVEMENT.

1,073,075.

Specification of Letters Patent.

Patented Sept. 9, 1913.

Application filed June 24, 1912. Serial No. 705,405.

To all whom it may concern:

Be it known that I, CHRISTIAN KECK, a citizen of the United States, and a resident of Crescent Springs, Kenton county, State 5 of Kentucky, have invented a certain new and useful Mechanical Movement; and I do declare the following to be a clear, full, and exact description of the invention, attention being called to the drawing which 10 accompanies this application and forms a part thereof.

This invention relates to mechanism for producing a compound movement of the movable or working member of the mechanism, the movement consisting of rotary and linear motions, which are both reciprocatory and proceed simultaneously.

In its practical application the mechanism may be utilized to operate for instance 20 the dolly-shaft of a washing-machine when it is desirable to rotate said shaft alternately in opposite directions, as well as to reciprocate it simultaneously in the direction of its axis.

25 The invention consists of the construction as hereinafter described and claimed and as illustrated in the accompanying drawing, in which:—

Figure 1, shows my device in side-elevation and with its parts in one of their extreme positions. Fig. 2, shows the same in a similar view with its parts in their other extreme position and in connection with modified means used for operation. Fig. 3, 35 is a top-view of the device, parts being removed on a horizontal section taken on line 3—3 of Fig. 1.

In the drawing, 7 is the working member, set in motion by the mechanism. As before 40 alluded to, it may be the dolly-shaft or a continuation of the same of a washing-machine, provided with a customary agitator 8. It is contained in bearings 9 and 10 which by preference form parts of the frame of the 45 mechanism. This frame consists of a base 11 which contains bearing 9 and of a standard 12, which at its upper end supports bearing 10. The base serves for securing the device to a suitable support 13 which, in case 50 of a washing-machine, may be the cover of the tub of the same. 14 is a pinion rigidly mounted on this shaft and 15 is a collar also rigidly secured to the shaft and spaced

from the pinion. Closely fitted between the two there is a slide 16, substantially disk-shaped and provided with a notched extension 17, fitted to engage a guide 18 provided on the standard. It is held in place between pinion and shoulder by the shaft which occupies a perforation in the same, 55 the engagement being however of a nature which does not interfere with the rotation of the shaft and with the parts connected thereto, viz, pinion 14 and collar 15.

19 is a pin which projects from the slide 65 and occupies the curved slot in a curved arm 20 which has a hub whereby it is pivotally supported in bearings 21—21, which by preference form integral parts of base 11. 22 is a lever-handle secured to this arm, 70 the connection being by preference a detachable one, and by means of screw 23, a recess being formed in the side of the arm which receives the connected end of the handle. A rack 24 is provided on arm 20 75 on one side of the slot therein and arranged to mesh into pinion 14. It will now be seen that if arm 20 is oscillated, shaft 7 will be raised and lowered alternately by reason of the operative connection between both, effected by means of slide 16, held on said shaft by pinion 14 and collar 15 and in engagement with slotted arm 20 by means of pin 19. The position of this latter within the slot of the arm is maintained by reason 80 of the notched extension 17, on slide 16 and in engagement with guide 18. At the same time rack 24, while passing back and forth across the face of pinion 14, which is rigidly connected to the shaft, effects the reciprocatory rotation of this latter. To reduce 85 the friction it is preferable to cover pin 19 with a roller-sleeve. In case of use in connection with a washing-machine, an effectual operation is obtained whereby the clothes to 90 be washed are alternately moved in the tub back and forth in two directions.

Connection for motor-drive may be readily made as shown in Fig. 2, by means of links 25 and 26, suitably arranged and 100 whereby the reciprocatory member 27 of the motor is connected to arm 20 by means of screw 23. The handle may be detached in that case if desirable and the screw replaced, to serve for attachment of one of the links. 105

According to extent of rotation of the

shaft, the pinion may be normal, or a mutilated one.

Having described my invention, I claim as new:

- 5 1. In a mechanical movement, the combination of a shaft, bearings to which it is fitted for rotary as well as for linear movement, a pinion rigidly mounted on it, and means to alternately rotate this pinion in opposite directions and to simultaneously move the same and the connected shaft back and forth in axial directions.
- 10 2. In a mechanical movement, the combination of a shaft, bearings to which it is fitted for rotary as well as for linear movement, an actuating device and complementary means in part on said device and on said shaft and whereby both are operatively connected to each other and in a manner 15 20 that manipulation of the actuating device causes interaction of the complementary means so as to reciprocate the shaft simultaneously in axial, as well as in rotary direction.
- 25 3. In a mechanical movement, the combination of a shaft, bearings to which it is fitted for rotary as well as for linear movement, a pinion rigidly mounted on it, and operating means comprising a rack which 30 is in mesh with this pinion and which serve

to reciprocate the shaft in rotary as well as in axial direction.

4. In a mechanical movement, the combination of a shaft, bearings to which it is fitted for rotary as well as for linear movement, a pinion rigidly mounted on it, and an oscillating arm in operative engagement with the shaft to reciprocate the same in axial direction and provided with a rack which is in constant engagement with the 35 40 pinion.

5. In a mechanical movement, the combination of a shaft, bearings to which it is fitted for rotary as well as for linear movement, a pinion rigidly mounted on it, an oscillating arm provided with a rack which meshes with the pinion, a connecting member moving with the shaft whereby this latter is connected to the arm to be moved thereby reciprocally in axial direction and 45 50 means to hold this connecting member to a movement which is parallel to the movement of the shaft.

In testimony whereof, I hereunto affix my signature in the presence of two witnesses. 55

CHRISTIAN KECK.
